DROP-SIDE CRIB

Leslie Peltier, Delphos, Ohio, assignor to The
Delphos Bending Company, Delphos, Ohio, a
corporation of Ohio

Application June 3, 1940, Serial No. 338,477

3 Claims. (Cl. 5—100)

This invention relates to cribs, or other small bedsteads of the type used by infants and small children. Such cribs possess high enclosing sides, one or more of which is vertically movable between elevated and lowered positions in order to provide convenient access to the interior thereof, such cribs being generally designated as "drop-side" cribs.

It is an object of the invention to improve and simplify the device used in such cribs in guiding and supporting the vertically movable side or sides thereof.

Prior devices, used in this connection, have been difficult and awkward to operate and by movement of the crib side, are quite often sprung or damaged so that they do not positively hold the movable crib side in its elevated position of crib closure.

In order to avoid these and other known objections present in such prior devices, the invention provides an improved supporting and guiding means for the movable side frame of a crib wherein said guide devices are pivotally carried by the adjoining corner posts for limited swinging movement in vertical planes passing transversely through the crib, the swinging movement of such guide devices enabling the movable side frame to be easily and positively engaged or disengaged with corner post studs used in maintaining the side frame in its elevated position, the movement of said guide devices further serving to avoid injury thereto whenever the side frame is operated.

For a further understanding of the invention, reference is to be had to the following description and the accompanying drawing in which:

Fig. 1 is a perspective view of a drop-side crib constructed in accordance with the present invention;

Fig. 2 is a transverse vertical sectional view taken through the crib illustrating the slideable side frame in its elevated and fastened position;

Fig. 3 is a similar view disclosing the pivotal movement of the guide devices employed in the mounting of the adjustable side frame;

Fig. 4 is a view similar to Figs. 2 and 3, and illustrating the side frame in its lowered position;

Fig. 5 is an enlarged vertical longitudinal sectional view taken, in part, through the corner post of the crib, the adjoining portions of the movable side frame and one of the associated guide devices;

Fig. 6 is a detail perspective view of one of the frame carried brackets.

Referring more particularly to the drawing, the numeral 1 designates a drop-side crib of the type to which the present invention is applicable. The crib is provided with the usual vertical corner posts 2, stationary end frames 3—3, a stationary side frame 4, stationary bottom frame members 5 and a vertically movable side frame 6. It is to the mounting of the side frame 6 that the present invention is particularly addressed.

As illustrated, the side frame 6 is formed to include parallel, vertically spaced horizontally extending rails 7, united by vertically disposed longitudinally spaced bars 8. The ends of the rails 7, as shown in Figs. 1 and 5, are provided with aligned vertical openings 9, each of which receives a guide rod 10.

Each of the guide rods 10 has its upper end laterally offset as at 11 and terminates in an up-standing and apertured ear 12, the latter being pivotally connected with the upper end of an adjoining corner post by means of a screw, rivet or other supporting stud 13. The rods 10 are disposed along the inner face of the corner post with which they are connected and are substantially coextensive with the full length or height of such posts. The lower end of each rod is loosely received within an opening 14 provided in a cooperative angle member 16. Each angle member is pivotally connected as at 17 in any desired manner with the lower portion of a complementary corner post.

The lower of the rails 7 of the side frame 6 has fixed to the under side thereof at each end a wear-receiving bracket 18. Each of these brackets terminates in a down-turned lip 19 in which is formed a slot or notch 20, the latter being of such size as to receive the shank of a headed stud or screw 21 projecting stationarily from the corner post 2.

In operation, when the side frame 6 is elevated to occupy its position of crib closure, as shown in Figs. 1, 2 and 5, the bifurcated lips 19 of the brackets 18 are positioned so that the same receive the shanks of the studs or screws 21, so that the weight of the side frame 6 will be imposed on and borne by the stud elements 21, the notches 20 in the lips 19 preventing lateral movement of the side frame 6 or the guide rods 10. To move the side frame 6 from its elevated position to its lowered position, as shown more particularly in Figs. 2 to 4 inclusive, the said side frame is elevated sufficiently so that the lips 19 of the brackets 18 are disposed above the stud elements 21. When this position has been attained, the side frame 6 and the guide rods 10

are swung outwardly about the axes of the screws 13, as shown in Fig. 3, in order to clear the stud elements 21. This swinging movement may be easily effected by the pivotal mountings provided for the upper and lower ends of the guide rods and, furthermore, it will be noticed that in obtaining these operating positions, the guide rods will not be flexed or bent to interfere with the free sliding movement of the side frame thereon. When the guide devices occupy the positions shown in Fig. 3, the side frame may be dropped until it assumes the position shown substantially in Fig. 4. To restore the side frame to its elevated position, these operations are reversed.

In view of the foregoing, it will be observed that the construction provided is characterized by its simplicity, ease and convenience in operation, positive action and economy in design. While I have shown and described a preferred form of my invention, nevertheless, it will be understood that the construction set forth is subject to considerable modification and the right is therefore reserved to employ all such modification that may be said to fall fairly within the purview of the following claims.

What is claimed is:

1. A drop-side crib comprising a pair of spaced vertical corner posts, a side frame arranged between and slidable vertically with respect to said posts, guide rods on which said frame is slidably mounted, said rods being pivoted at their upper ends to adjoining portions of said posts, pivoted devices carried by the lower portions of said posts for the reception of the lower ends of said rods, stationary studs projecting from the corner posts intermediately of their lengths, and

means carried by the lower portions of said side frame for engagement with said studs, whereby to retain the side frame in an elevated position of crib closure.

5. 2. A drop-side crib comprising a pair of spaced vertical corner posts, a side frame arranged between said posts, guide rods having their upper ends pivotally connected with said posts and depending vertically therefrom, said frame having openings provided in the ends thereof for the reception of said guide rods, angle members pivoted to the lower ends of said posts, said members being apertured to loosely receive the lower ends of said rods, stationary studs projecting from said corner posts, and bifurcated brackets carried by said side frames for engagement with said studs when said frame occupies an elevated position.
10. 3. In a crib, a pair of corner posts, a rod having a laterally offset upper end secured to the opposed face of each corner post, said rods being pivotally movable about the longitudinal axis of the securing means in a plane parallel to the longitudinal axis of said post, a side frame having 15. openings for the slidable reception of said rods, stop means projecting from said posts, bracket means having bifurcated ends secured to the lower portions of said side frame, said bracket means being engaged with said stop means to retain said frame in an elevated position and prevent undesired pivotal movement of said rods, and means pivotally secured to said corner posts and engaging the lower ends of said rods for limiting the downward movement of said frame and 20. the swinging movement of said rods.
25. 35. LESLIE PELTIER.
